THOMAS DOLAN, OF PHILADELPHIA, PENNSYLVANIA.

Design No. 3,500, dated May 18, 1869.

DESIGN FOR A STOCKING-FABRIC.

The Schedule referred to in these Letters Patent and making part of the same.

To all whom it may concern:

Be it known that I, THOMAS DOLAN, of Philadelphia, county of Philadelphia, State of Pennsylvania, have originated a new Design for a Stocking-Fabric; and I do hereby declare that the accompanying drawing, and following explanation thereof, form a full, clear, and exact description of the said design.

In the drawing, the figure represents sufficient of the stocking-fabric to illustrate my design, the latter consisting of stripes A A, each stripe being composed of the zigzag ribs, clearly represented in the drawing, there being between these ribs a zigzag stripe, a.

Irrespective of the colors employed,
• I claim—
The design for a stocking-fabric, substantially as described, and as represented in and by the accompanying drawing.

In testimony whereof, I have signed my name to this specification, in the presence of two subscribing witnesses.

THOMAS DOLAN.
